UNITED STATES PATENT OFFICE.

EDMOND A. WARREN, OF BROOKLYN, NEW YORK, ASSIGNOR TO HIMSELF
AND THOMAS J. MOORE, OF SAME PLACE.

TAG.

SPECIFICATION forming part of Letters Patent No. 269,753, dated December 26, 1882.

Application filed January 21, 1882. (No model.)

To all whom it may concern:

Be it known that I, EDMOND A. WARREN, of Brooklyn, in the county of Kings and State of New York, have invented a certain new and useful Improvement in Tags, of which the following is a specification.

My invention relates to merchandise or shipping tags, which are commonly made of paper; and the object of the invention is to prevent the tearing of such tags, and also prevent them from curling up or being rumpled in use.

To this end the invention consists in a paper tag composed of two plies or thicknesses, and provided with a strengthening-frame composed of a wire or string extending around the tag near the margin, thereby conforming to the shape of the tag, and secured between the two plies or thicknesses by pasting or cementing them together both inside and outside of the frame.

In the accompanying drawings, Figure 1 represents a face view of a tag embodying my invention. Fig. 2 represents a transverse section thereof. Fig. 3 represents a face view of one of the plies or thicknesses of which the tag is composed and the strengthening wire or string, and Fig. 4 represents a face view of a tag of modified form.

Similar letters of reference designate corresponding parts in all the figures.

A designates the tag, which is composed of two plies or thicknesses of Manila paper or other material of which such tags are usually formed, and which are of the same size and outline.

B designates a wire or string, which is inserted between the two plies or thicknesses, as clearly seen in Fig. 2, and which is carried entirely around the margin of the tag at a little distance from its edge, so as to form a strengthening-frame. The two end portions of the wire or string B issue from between the plies or thicknesses, and they may be twisted at B', Figs. 1 and 3, and be prolonged beyond the twist, so as to form ends B², which are long enough to provide for attaching the tag conveniently to any article on which it is desired to use it. Instead of having the two end portions of the wire or string prolonged to any

considerable length, I may form in the wire or string B a loop or eye, a, as seen in Fig. 4, through which the tying string or wire may be inserted. After the wire or string B is inserted the two plies or thicknesses are cemented, glued, or pasted together throughout their extent and on both sides of the wire or string B. This holds the two plies together, and secures the wire or string properly in place.

Where an ordinary tag commences to tear, only the strength of the paper prevents it from being torn entirely in two; but if the margin of this tag begins to tear it will stop as soon as the strengthening wire or string is reached.

I am aware that tags have been made in which the fastening wire or device is secured to the tag by folding over and pasting down a portion of the tag, thereby forming two plies or thicknesses, between which the wire or device is held; but this has been done simply to prevent the tearing out of the fastening device, and not with a view to prevent, and has not prevented, the tearing of the tags elsewhere.

I do not claim a tag of the kind just described as included in my invention. By my invention I form a strong frame, surrounding the tag near its margin, which will protect the tag against being torn at any point, as the slightest tear will be prevented from extending inward by the frame, and which will also prevent the curling up or rumpling of the tag.

What I claim as my invention, and desire to secure by Letters Patent, is—

The tag A, composed of two plies or thicknesses, and provided with the strengthening-frame B, composed of a string or wire extending around the tag near the margin and secured between the two plies or thicknesses by pasting or cementing them together both inside and outside the frame, whereby the tag is protected all around the margin against being torn, and is prevented from curling up or becoming rumpled, substantially as herein described.

EDMOND A. WARREN.
